US00D790465S

(12) **United States Design Patent** (10) **Patent No.:** **US D790,465 S**
(45) **Date of Patent:** **** Jun. 27, 2017**

(54) **POWER ADAPTER**

(71) Applicant: **Zeshun Zhao**, Jinpenxu Town (CN)

(72) Inventor: **Zeshun Zhao**, Jinpenxu Town (CN)

(73) Assignee: **DONGGUAN ZHAOSHUN ELECTRONICS TECHNOLOGY CO., LTD**, Dongguan (CN)

(**) Term: **15 Years**

(21) Appl. No.: **29/568,574**

(22) Filed: **Jun. 20, 2016**

(51) **LOC (10) Cl.** **13-02**

(52) **U.S. Cl.**

USPC **D13/110**

(58) **Field of Classification Search**

USPC ..... D13/101, 102, 107, 108, 110, 112, 118, D13/119, 123, 133, 138.1, 162, 184, 199 CPC H02P 27/04; H02P 27/06; H02P 27/047; H02P 2201/09; H02P 2201/11; H02M 2001/0067; H02M 2001/007; H02M 2001/0045; H02M 2001/0083; H02M 2001/009; G06F 1/00; G06F 1/188; G06F 1/189; G06F 1/26; G06F 11/2015; H01R 13/66; H01R 13/60; H01R 13/72; H01R 13/6675; H01R 31/065; H05K 5/0021; H05K 5/0208; H05K 5/0247; H05K 5/00

(57) **CLAIM**

The ornamental design for a power adapter, as shown and described.

DESCRIPTION

FIG. 1 is a front perspective view of a power adapter showing my new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a rear perspective view thereof.

The broken lines in the drawings are for the purpose of illustrating portions of the power adapter that form no part of the claimed design.

1 Claim, 2 Drawing Sheets
